CLAIM

The ornamental design for a reagent pack, as shown and described.

DESCRIPTION

FIG. 1 is a right rear top perspective view of an embodiment of a reagent pack showing my new design and showing unclaimed structure in broken lines;

FIG. 2 is a right front bottom perspective view thereof;

FIG. 3 is a right elevation view thereof;

FIG. 4 is a left elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is a right rear top perspective view of another embodiment of the reagent pack showing my new design and showing unclaimed structure in broken lines;

FIG. 10 is a right front bottom perspective view thereof;

FIG. 11 is a right elevation view thereof;

FIG. 12 is a left elevation view thereof;

FIG. 13 is a rear elevation view thereof;

FIG. 14 is a front elevation view thereof;

FIG. 15 is a top plan view thereof; and,

FIG. 16 is a bottom plan view thereof.

The broken lines are included for the purpose of illustrating portions of the reagent pack that form no part of the claimed design.
